US0D1091144S

(12) **United States Design Patent** (10) **Patent No.:** **US D1,091,144 S**
(45) **Date of Patent:** **** Sep. 2, 2025**

(54) **SURFACE PATTERN FOR SEATS**

(71) Applicant: **KETER HOME AND GARDEN PRODUCTS LTD.**, Herzliya (IL)

(72) Inventor: **Hanna Spaander**, Ede (NL)

(**) Term: **15 Years**

(21) Appl. No.: **35/523,779**

(22) Filed: **Dec. 9, 2024**

(80) **Hague Agreement Data**

Int. Filing Date: **Dec. 9, 2024**

Int. Reg. No.: **DM/243559**

Int. Reg. Date: **Dec. 9, 2024**

Int. Reg. Pub. Date: **Jan. 31, 2025**

(30) **Foreign Application Priority Data**

Jun. 10, 2024 (IL) 72676

(51) **LOC (15) Cl.** **05-03**

(52) **U.S. Cl.**

USPC **D5/47**

(57) **CLAIM**

The ornamental design for a surface pattern for seats as shown and described.

DESCRIPTION

1. Surface pattern for seats

1.1 : Perspective [Top, front, right side]

1.2 : Front

1.3 : Reference view

1.4 : Left

1.5 : Right

1.6 : Top

1.7 : Bottom

1.8 : Back

1.9 : Reference view

The parts colored in blurry white separated by dashed lines in reference views 1.3 and 1.9 show the pattern as part of the seat and are shown to illustrate portions of the seat, which form no part of the claimed design; the dashed lines surrounding the dark grey areas represent the boundaries of the claimed design and form no part thereof.

1 Claim, 9 Drawing Sheets
